UNITED STATES PATENT OFFICE.

HENRY B. PELTON, OF MISHAWAKA, INDIANA.

BOOT-TREE.

SPECIFICATION forming part of Letters Patent No. 659,181, dated October 2, 1900.

Application filed July 18, 1900. Serial No. 24,085. (No model.)

To all whom it may concern:

Be it known that I, HENRY B. PELTON, of Mishawaka, in the county of St. Joseph and State of Indiana, have invented certain new and useful Improvements in Boot-Trees; and I hereby declare that the following is a full, clear, and exact description thereof, reference being had to the accompanying drawings, which form part of this specification.

This invention is an improvement in collapsible trees particularly designed for use in the making of felt boots. Heretofore these trees have generally been made with a divided sole, one portion of which in collapsing telescopes into the other or moves upon or relatively to the other in some way, so that the length from the heel to the toe varies and is not the same when the tree is in the collapsed state as it is when the tree is in the extended state. This stretching sometimes amounts to three or four inches and constitutes the weak point or defect in nearly all trees heretofore made, because this extension of the limited portion of the blank puts undue strain upon the foot of the boot and results in defects in the formed boot. In the improved tree forming the subject of this invention there is no extension of the sole part, and hence no undue strain on the blanks and no faulty boots. Each blank is perfectly formed and the feature of having the entire sole portion (heel and toe) in one piece and allowing the top of the boot to be moved upon this single-sole piece is a feature of particular value that renders the improved tree superior to all that have preceded it.

The invention therefore consists in the novel construction and combination of parts hereinafter described and claimed, and illustrated in the accompanying drawings, in which—

Figure 1 is a sectional view of the tree expanded. Fig. 2 is a similar view thereof collapsed. Figs. 3, 4, and 5 are details.

The tree is made practically in four parts—the sole portion, the upper portion, and the front and back portions of the leg of the boot. The "upper" portion C of the tree is slotted at c in its toe to admit the wire loop L on the sole portion, and passing across the toe and part C is pin P, which engages the loop L and secures the upper C to the sole portion

of the tree, yet allows the two parts to move backward and forth upon each other when the tree is collapsed. The front leg portion D is 55 pivoted to the upper part C, as shown, and part C is provided with a rearwardly-projecting extension G, by means of which it is pivotally attached to the back leg part A of the tree. The sole portion B is also pivoted to 60 the rear leg part A at N and is provided with a latch H, which when the sole B is down in its proper position for the forming of the boot, Fig. 1, engages with a shoulder g on the upper C. In Fig. 1 the tree is shown 65 with the parts set as they should be when it desired to form a boot. A loop J is pivoted to the back part of the leg A and has a cross-piece j near its upper bend, as shown, and the front part D of the leg is provided with a 70 boss d. When the tree is collapsed, this loop J is thrown upward and of course will fold up within the leg of the boot, as shown.

To put a new felt blank over the form, the latch H is raised, and the toe of the boot can 75 then be lifted up, as shown in Fig. 2. This will throw part A downward and toward part D, while the sole portion D will turn upwardly until it is finally almost parallel with part A. The entire tree will then have its parts arranged substantially as shown in Fig. 2, and the blank felt form of a boot can then be 80 readily stretched over the tree and brought until the end of the blank comes in contact with the toe end of the part B. Then part B 85 is forced down until the parts assume the position shown in Fig. 1, when the latch H will engage with shoulder g and lock the extended tree and blank in boot form. The boot is then treated and dried, after which the tree 90 is collapsed and withdrawn. By turning the boot up and tapping it on a table the latch H will drop by gravity out of engagement with shoulder g, and the tree can then be collapsed and withdrawn from the boot, as described. 95

The advantages of this construction are as follows: In trees as heretofore made the distance between the point of the toe and the heel will vary—that is to say, when the tree is in a vertical position, so that the blank can 100 be slipped over it, the sole portion will measure, say, a certain number of inches from the toe to the heel; but when the tree is extended and the sole portion brought down to its place

the distance from the heel to the point of the toe will be increased, throwing the parts away from each other—and as the heel is usually on the rear leg part and the toe secured to the front leg part these portions will be moved away from each other, so that material of which the felt boot is made is subjected to a great strain and this produces defects about the heel of the boots made on such trees which makes them of an inferior grade by weakening the boot at the points of tension. It is evident, however, that in this present invention, since the sole portion is all in one piece and as the distance or length from the heel to the toe thereof is constant no undue strain will be placed upon the felt. Therefore there are no weak points produced in the boot by the undue stretching of the foot when the boot is treed.

In this invention the sole portion is hinged to the rear leg portion and is practically immovable except around the point where it is pivoted or hinged and the sole is one uniform length, and hence no undue strain is put on the inclosing portion of the boot-blank. The motion of the parts in expanding the boot puts simply an expanding stretch sufficient to give the toe of the boot and the upper part of it its proper form, and as the toe of the tree is thrown downward a certain fullness of material is supplied for the front part of the boot where the ankle comes sufficient to allow the filling out of the form without undue strain on any part.

When it is desired to expand the leg of the boot after the foot is drawn down, a hooked rod Z may be inserted and caught over the cross-piece j of the loop J, and as the latter is drawn downward it is evident that it will press against the front part of the leg and will separate the portions A and D of the leg until it comes in contact with the boss d, and as it is farther drawn downward it will draw the front portion of the leg of the tree downward, and thus furnish another means for expanding the tree and bringing the foot down to its proper position, so that the setting of the foot and the expansion of the tree can be done with the one operation of pulling down this loop, or, if desired, the foot could be collapsed first and the leg could be expanded, pulling down the loop afterward. Either method of operating the tree would be perfectly practicable.

Having thus described my invention, what I claim as new, and desire to secure by Letters Patent, is—

1. In a collapsible tree, the combination of the front and rear leg portions, the upper portion, and the sole portion hinged at its heel end to the rear leg portion and having a sliding connection at its toe end with the upper, for the purpose and substantially as described.

2. In a collapsible tree, the combination of the front and rear leg portions, the upper

portion hinged to the front and rear leg portions, and the sole portion hinged at its heel end to the rear leg portion and having a loop on its toe end, and a pin on the upper portion of the tree engaging said loop, for the purpose and substantially as described.

3. The combination in a collapsible tree, of the front and rear leg portions, the upper portion pivoted to the front leg portion and having an extension by which it is also pivoted to the rear leg portion, the sole portion hinged at its heel end to the rear leg portion and having a loop on its toe end loosely engaging in a slot in the said upper portion, substantially as described.

4. The combination in a collapsible tree, of the front and rear leg portions, the upper portion pivoted to the front leg portion and having an extension by which it is also pivoted to the rear leg portion, the sole portion hinged at its heel end to the rear leg portion and having a loop on its toe end, and a pin on the upper portion engaging said loop, said loop being adapted to play through a slot in said upper portion, and a latch pivoted to the sole portion near the heel end thereof and adapted to engage an abutment on the upper portion to lock the tree in extended position, substantially as described.

5. The combination in a collapsible tree of the front and rear leg portions, the upper portion pivoted to the front leg portion and having an extension by which it is also pivoted to the rear leg portion and the sole portion hinged at its heel end to the rear leg portion and having a loop on its toe end adapted to play through a slot in the said upper portion, with a latch adapted to lock the tree in extended position, and a link pivoted to one leg portion and adapted to engage the other to expand the leg for the purpose and substantially as described.

6. The combination in a collapsible tree of the front and rear leg portions, the upper portion pivoted to the front leg portion and having an extension by which it is also pivoted to the rear leg portion, the sole portion hinged at its heel end to the rear leg portion and having a loop on its toe end, and a pin on the upper portion engaging said loop, the loop being adapted to play through a slot in the said upper portion, and a latch pivoted to the sole portion near the heel end thereof adapted to engage an abutment on the upper portion to lock the boot in extended position, and a link pivoted to one leg portion and adapted to engage the other leg portion, for the purpose and substantially as described.

In testimony that I claim the foregoing as my own I affix my signature in presence of two witnesses.

HENRY B. PELTON.
